UNITED STATES PATENT OFFICE.

ROY P. M. DAVIS, OF MOUNT UNION, PENNSYLVANIA.

BRICK-MAKING MACHINE.

Application filed September 2, 1926. Serial No. 133,186.

My invention relates to method of and machines for making brick and more particularly to means for placing the molded brick upon the pallets.

5 Heretofore it has been the practice to fill the mold on a bed plate and then invert or turn the mold over in depositing it upon the pallet. Another method has been to fill the mold with the brick making material or mud 10 while the mold rests upon a plunger and then remove the brick by pushing or lifting the same off the plunger. These methods have proven particularly objectionable when soft mud is used, due to the fact that 15 the mud settles during the tilting or inverting step, and where the brick is lifted or pushed from the plunger a large percentage of broken, misshapen and otherwise damaged bricks are produced.

20 The object of my invention is to overcome the objections mentioned by placing the molded brick upon the pallet before taking the brick out of the mold and without inverting the mold.

25 Other and further objects and advantages of my invention will be apparent as the specification is considered in connection with the accompanying drawings, in which:

Figure 1 is a plan view of the device;

30 Figure 2 is a side view thereof;

Figure 3 is a plan view of a modification; and

Figure 4 is a side view of the device illustrated in Figure 3.

35 Referring more particularly to the drawings wherein like reference numerals refer to corresponding parts throughout the several views, 1 denotes a suitable base upon which is mounted an anvil plate or block 3, a pedestal 4 being employed for this purpose.

40 A pallet 5 of any ordinary and suitable construction rests upon and is supported by the anvil plate or block 3, the latter being provided with a recess 6 to receive the body 45 of the pallet and maintain the top surface thereof flush with the top 7 of the anvil plate or block, the rolled edges 8 of the pallet 5 being accommodated between the forward and rear extensions 9 and 10 respectively of 50 the anvil plate or block.

55 Resting loosely upon the top surfaces of the anvil plate or block 3 is a thin flat smooth liner plate 11, preferably of tin, of sufficient length and width to substantially cover the pallet. It is upon this plate 11 that the sectional mold 12 is placed preparatory to the

filling and slicking operations, which are performed by any well known and suitable mechanism (not shown).

When the mold 12 has been filled with 60 brick making material and the molded brick have been slicked, the filled mold is deposited directly upon the pallet by withdrawing the liner plate from between the mold and pallet, after which operation the 65 mold is stripped from the brick by stripping mechanism (not shown).

The liner plate 11 is withdrawn from between the mold and the pallet by means of a lever 13 pivotally mounted upon the base 70 1 as at 14, at its lower end, and pivotally connected adjacent the handle portion 15 on its upper end to the rear end of the liner plate as at 16. Any suitable mechanical means (not shown) may be employed to actuate the lever 13, or the latter may be manually manipulated by grasping the handle portion 15 thereof.

In Figures 3 and 4 I have illustrated a modified form of the invention adapted to 80 be employed in a brick making machine wherein the stripping mechanism is located at a point removed from the filling and slicking station. In this form of the invention an anvil plate 3' is supported upon the 85 base 1' by means of posts or uprights 4'. The anvil plate 3' is formed with an enlarged or thickened rear portion 17 adapted to receive and support the sectional mold 12' during the filling and slicking operation. The forward portion of this anvil plate 3' is cut away or reduced in thickness, to form a recess 18, adapted to receive the pallet 5' therein, the depth of the recess being such that the top of the pallet is flush 90 with the top of the enlarged portion 17 of the anvil plate.

As in the preferred form of the invention, a liner plate 11' is employed which is similar in all respects to the plate 11 with the exception that the former plate is of sufficient length and width to cover the enlarged portion 17 and to extend over the pallet receiving recess 18. It will thus be seen that the entire top of the anvil plate 3', including the pallet receiving recess 18 and the pallet 5' therein, are covered by the thin liner plate 11', the purpose of the liner plate 11' being identical to that of the liner 11 of the preferred form of my invention, namely to facilitate the placing of the mold 12' with brick therein upon the pallet 5'.

In practice the sectional mold 12' after the filling and slicking operations have been performed, is slid from A position forwardly along the top of the liner plate 11' by means 5 of pusher arms 20 until the mold is in B position directly over the top of the pallet 5'. The lever 13' pivotally connected to the base 1 and the liner plate 11' as at 14' and 16' respectively, is withdrawn from between the 10 mold and the pallet in the manner previously described. Any suitable mechanical means (not shown) may be employed for actuating the pusher arms, or the latter may be manually actuated.

Having thus described my invention, what I claim as my invention is:

1. A brick making machine comprising an anvil plate adapted to support a pallet there-

on, a liner plate, a mold adapted to rest on said liner plate above said pallet and means 20 for withdrawing said liner plate from between said mold and said pallet.

2. A brick making machine comprising an anvil plate having a mold supporting surface and a pallet supporting surface at 25 different levels, with mold and pallet thereon, a liner plate between the mold and the mold supporting surface and extending over and above said pallet, means for moving the mold after the filling operation across 30 said liner plate to a position thereon above said pallet, and means for withdrawing the liner plate from between the mold and the pallet.

In testimony whereof I affix my signature.
ROY P. M. DAVIS.
